United States Patent Office

Des. 215,372
Patented Sept. 23, 1969

215,372

FLASHING SIGNAL UNIT

Robert D. Kahn, 24 Maple Ave.,
Rockville Centre, N.Y. 11570

Continuation-in-part of design application Ser. No.
9,385, Nov. 13, 1967. This application May 23,
1968, Ser. No. 12,593

Term of patent 14 years

Int. Cl. D29—99

U.S. Cl. D72—1

FIG. 1

FIG. 5

FIG. 2

FIG. 3

FIG. 4

FIG. 1 is a perspective view of the design for a flashing signal unit;

FIG. 2 is a right side elevational view thereof, the left side elevational view being identical;

FIG. 3 is a front elevational view thereof;

FIG. 4 is a bottom plan view thereof; and

FIG. 5 is a perspective view of another embodiment of a design shown in FIGS. 1 through 4.

This is a continuation-in-part of design application Ser. No. 9,385, filed Nov. 13, 1967, now Design Patent No. D. 212,722.

I claim:

The ornamental design for a flashing signal unit, as shown and described.
